S. E. DOUGLASS.
PICTURE FRAME HOLDER AND HANGER.
APPLICATION FILED JAN. 31, 1918.

1,300,137.

Patented Apr. 8, 1919.

UNITED STATES PATENT OFFICE.

SAMUEL E. DOUGLASS, OF BEAUFORT, NORTH CAROLINA.

PICTURE-FRAME HOLDER AND HANGER.

1,300,137.

Specification of Letters Patent.

Patented Apr. 8, 1919.

Application filed January 31, 1918. Serial No. 214,690.

To all whom it may concern:

Be it known that I, SAMUEL E. DOUGLASS, a citizen of the United States, residing at Beaufort, in the county of Carteret and 5 State of North Carolina, have invented certain new and useful Improvements in Picture-Frame Holders and Hangers; and I do hereby declare the following to be a full, clear, and exact description of the invention, such as will enable others skilled in the 10 art to which it appertains to make and use the same.

This invention relates to picture frame holders, and hangers, and the primary object of the invention is to provide an improved means for hanging picture frames in which the frame can be raised or lowered without necessitating the use of a step ladder, and after the picture molding hooks 15 have been once placed in position, the frames can be readily and easily removed without the use of a step ladder and without necessitating the removal of the picture frame hooks.

20 Another object of the invention is the provision of an improved means for hanging pictures in which the supporting cord is slidably associated with the picture frame, so that the weight of the frame will automatically hold the picture in the center of 25 the cord, and thus assume a straight position.

30 A further object of the invention is the provision of a device of the above character, which can be readily and easily applied to picture frames of all sizes and one which is durable and efficient in use, one that is simple and easy to manufacture, and one that can be placed upon the market at a 35 reasonable cost.

40 With these and other objects in view, the invention consists in the novel construction, arrangement and formation of parts, as will be hereinafter more specifically described, 45 claimed and illustrated in the accompanying drawing, forming a part thereof, in which:

Figure 1 represents a side elevation of a picture frame hung in accordance with my 50 invention.

Fig. 2 represents a side elevation of the picture frame hung in accordance with my invention showing the holder and hanger attached thereto.

55 Fig. 3 is a vertical transverse section taken on the line 3—3 of Fig. 2.

Fig. 4 is a detail section through one of the bars of the picture holder and taken on the line 4—4 of Fig. 2.

Fig. 5 is a transverse sectional taken 60 through the bars of the picture holder showing the same slidably associated with each other.

Fig. 6 is a transverse section taken through one of the picture molding hooks showing 65 the same in position on a picture molding, and

Fig. 7 is a detail perspective view of one of the picture molding hooks.

Referring to the drawing in detail, where 70 in similar reference numerals designate corresponding parts, throughout the several views, the numeral 1 generally indicates the improved picture hanger and holder, attached to a picture frame 2, which may be 75 of any size or shape. The picture frame holder 1 includes a pair of slidably associated bars 3 and 4, the lower bar 4 having its longitudinal edges bent upwardly and then inwardly toward each other to provide 80 guides 5 for slidably receiving the upper bar 3. The opposite outer terminals of the bars 3 and 4 are each provided with apertures 6 for receiving suitable detachable fastening elements 7, which extend through 85 the picture frame 2 and holds the bars in position. The bars 3 and 4 can be readily moved toward or away from each other, so that the same can be secured to larger or smaller picture frames. The upper bar 3 is 90 provided with an outwardly extending hook 8 on each side edge thereof adjacent to the upper terminal of the same and these hooks 8 slidably receive the picture wire or cord 9. The picture wire or cord 9 is preferably 95 provided with its ends tied so that an enclosed loop is formed and the lower end of the cord receives the removable retaining hook 10, which is associated with the supporting bars 3 and 4. The hook 10 is pref- 100 erably bent in a substantially semi-circular configuration and has its upper end curved to provide the eye 11 for receiving the picture cord 9. The bars 3 and 4 are provided with a plurality of openings 12' and the sub- 105 stantially semi-circular curved portion of the hook 10 is adapted to be inserted in any one of the same. A hook 12 is secured to each upper corner of a frame and these hooks also slidably receive the supporting 110 picture frame wire or cord 9.

A picture or molding hook 13 is bent to

form the ordinary double hook for engaging the picture molding and receiving the wire 9. The picture molding hook 13 includes a body 14 having a downwardly extending bill 15 for engaging the picture molding and the upwardly extending bill 16 for receiving the picture wire. The bill 16 has its terminal slightly bent inwardly as at 17 to prevent the accidental displacement of the cord.

In operation of the improved device, the bars 3 and 4 are applied to a picture frame as described above and the picture wire 9 is looped over the bill 16 of the picture molding hook and the same is threaded through the eye 11 of the hook 10, which is positioned in any one of the recesses 12 according to the distance to which the picture is to be hung in relation to the picture molding and then the picture wire is hooked over the hooks 8 and then around the hooks 12.

From the foregoing description it can be seen that after the picture molding hook 13 has been placed in position, and the picture wire 9 hung on the same, the picture can be readily removed from or placed on the supporting cord 9. When it is desired to remove the same, all that is necessary is to remove the hook 10 and the cord 9 from around the hook 8 and the hooks 12.

In practice, I have found that the form of my invention, illustrated in the accompanying drawings and referred to in the above description, as the preferred embodiment, is the most efficient and practical; yet

realizing the conditions concurrent with the adoption of my device will necessarily vary, I desire to emphasize the fact that various minor changes in details of construction, proportion, and arrangement of parts may be resorted to, when required without sacrificing any of the advantages of my invention as set forth.

What is claimed is:—

1. A picture frame hanger and holder comprising a supporting bracket including a pair of slidably associated bars, means securing the outer terminals of the bars to a picture frame, a flexible member associated with said bracket, the bars of the bracket having a plurality of apertures formed therein, and a hook slidably receiving the flexible member and adapted to be positioned in any one of the apertures, as and for the purpose specified.

2. In a device of the class described, a picture frame, a bracket including a pair of adjustable bars, means securing the outer terminals of the bars to a picture frame, hooks carried by the upper side edges of the bracket, hooks carried by the upper corners of the picture frame, a hook adjustably associated with the bracket, and a flexible member slidably engaging each of the hooks, as and for the purpose specified.

In testimony whereof I affix my signature in presence of two witnesses.

SAMUEL E. DOUGLASS.
